(57) **CLAIM**

The ornamental design for a rotating arm flat top scale, as shown and described.

DESCRIPTION

FIG. 1 is top perspective view of the rotating arm flat top scale of my design.

FIG. 2 is a top view of the same rotating arm flat top scale as shown in FIG. 1.

FIG. 3 is a top side view of the same rotating arm flat top scale as shown in FIG. 1.

FIG. 4 is a left side view of the same rotating arm flat top scale as shown in FIG. 1.

FIG. 5 is a right view of the same rotating arm flat top scale as shown in FIG. 1; and,

FIG. 6 is a bottom side view of the same rotating arm flat top scale as shown in FIG. 1.

The bottom of the rotating arm flat top scale of the invention is flat and is not part of the claimed design.

1

EX PARTE
REEXAMINATION CERTIFICATE
ISSUED UNDER 35 U.S.C. 307
THE PATENT IS HEREBY
AMENDED AS INDICATED
BELOW.

2

AS A RESULT OF REEXAMINATION, IT HAS BEEN
DETERMINED THAT:

5 The sole design claim is cancelled.
